COMBINED TUMBLER AND TOOTHBRUSH HOLDER

Leslie E. Lanczi, 24 Radcliffe Road, Montreal West,
Quebec, Canada

Filed Sept. 27, 1965, Ser. No. 87,160

Term of patent 7 years

(Cl. D4—3)

FIG. 3

FIG. 1

FIG. 4

FIG. 2

I claim:

The ornamental design for a combined tumbler and toothbrush holder, as shown.
